UNITED STATES PATENT OFFICE.

MORLEY PUNSHON REYNOLDS, OF CLEVELAND HEIGHTS, OHIO, ASSIGNOR TO THE W. S. TYLER COMPANY, OF CLEVELAND, OHIO, A CORPORATION OF OHIO.

SCREEN.

1,333,220.

Specification of Letters Patent. Patented Mar. 9, 1920.

Application filed March 21, 1919. Serial No. 284,185.

To all whom it may concern:

Be it known that I, MORLEY PUNSHON REYNOLDS, a citizen of the United States, and a resident of Cleveland Heights, county of Cuyahoga, and State of Ohio, have invented a new and useful Improvement in Screens, of which the following is a specification, the principle of the invention being herein explained and the best mode in which 10 I have contemplated applying that principle, so as to distinguish it from other inventions.

The present improvements relate to a method of strengthening or increasing the 15 life of woven wire screens which are used in screening machines for grading various materials. A further object of the invention is the provision of an improved screen cloth which will not be subject to breakage or 20 crystallization of the material along those edges which are held or clamped to the frame of the screening machine.

In such machines the screen cloth is often vibrated continuously at high speed, with 25 the result that it is bent backward and forward very rapidly along the line of its attachment to the sides of the frame, and the inevitable result of this action is to cause the wires of the screen to crystallize at this 30 point, and finally to break. This is particularly noticeable in a screen cloth in which a hard wire is used, as of course the harder the wire the quicker it will crystallize under vibration. To the accomplishment of the 35 foregoing and related ends, said invention, then, consists of the means hereinafter fully described and particularly pointed out in the claims.

The annexed drawing and the following 40 description set forth in detail one method and one product exemplifying my invention, such disclosed procedure and product constituting however, but one of various applications of the principles of my invention. 45 Figure 1 is a transverse section through a screen cloth showing one method of attachment to a frame; and Fig. 2 is also a transverse section illustrating apparatus which may be used to strengthen the marginal 50 portions of such a screen.

Various means have been tried in an attempt to prevent the crystallization and subsequent breakage of the wires of the screen at the point of attachment to the 55 frame, but, although this trouble has been a

continual one in the use of all screens during the period in which woven wire screens have been used, no satisfactory method of preventing this breakage has heretofore been found.

My improved method of strengthening the screen along the marginal portions against crystallization and breakage under vibration involves the softening of the marginal portion of the screen by passing this edge portion only through a heat-treating or annealing furnace in order to soften the wires of the screen along the edges. At the same time care is taken that the remainder of the screen cloth is not exposed to the annealing heat and is therefore unaffected by the heat treatment of the marginal portion. The result of this treatment is to very materially soften, and hence strengthen under vibration, the edge portions of the screen, 75 while preserving the strength and resiliency of the screen cloth proper, and hence its ability to resist wear of the materials passing thereover and to vibrate freely under impulses imparted to it. The treatment also 80 removes the results of the previous drawing and working of the wire. It is of course well known that soft wire may be bent backward and forward many more times before breaking than hard wire, and it is this quality of the wires of the screen cloth that I make use of in order to lengthen the life of the screen under vibration at the point of attachment to the frame.

In Fig. 1 of the drawings I have shown a 90 woven wire screen 1, having its edge portions 2 turned in and firmly and evenly gripped by a reversely bent metal strip 3, which is one means that I have found of securing a uniform grip on the edge of the 95 screen in such a way as to engage and hold each transverse wire thereof. When this screen is vibrated it is bent at approximately the point indicated by the arrows 4 in Fig. 1, and as the vibrations are extremely rapid, 100 being never less than several hundred a minute, the extent of the bending action on the screen will be readily appreciated. The result of this bending action is of course to crystallize the wires at the point of bending, 105 causing the breakage of these wires in time and the failure of the screen.

In Fig. 2 I have shown more or less diagrammatically an apparatus for treating a screen in the manner described, this appa- 110

2

5 apparatus consisting of a suitable hood 5, disposed above a screen-receiving table 6. At one side of the table, and slightly below the edge of the same, is mounted a long tubular burner 7, which may be supplied with suitable fuel, such as gas and air through conduits 8 and 9, for producing a flame of the desired temperature. This flame is projected directly upward and is then turned to 10 ward the center of the hood by means of an angle plate 10. In the operation of this apparatus a woven wire screen is placed flat upon the table 6, with the edge which is to be softened on the inside, and is then pushed 15 against the side of the hood 5 below the angle iron 10, which is spaced a sufficient distance from the inner edge of the table to allow an inch or an inch and a half of the screen to project across above the flame from 20 the burner 7. It is then necessary merely to hold the screen in that position until the edge portion has been heated and annealed to the desired softness, which requires but a very few minutes in the case of finely woven 25 screen. The screen is then removed, reversed, and the other edge treated.

This improved method of making, or rather strengthening, the screen is of particular importance in connection with that 30 type of screen which is now so widely sold where tonnage and resistance to wear are important features. The advantage of the present invention in connection with wire screen is that it remedies the one remaining 35 chance of failure of the screen, which is the breakage that occurs along the margin of the screen where it is held in the frame, due to

the vibration or bending of this part. Actual use of this type of screen, constructed in accordance with my improved method, has 40 shown an average increase in the life of the screen which is very material and which decreases the cost of the screening material and greatly increases the value and life of the individual screens. This improved 45 method softens and renders more flexible the edge portions of the screen where it is gripped or attached to the frame without in any way affecting the character of the remainder or body portion of the screen, 50 which retains its resilience and resistance to wear that has brought it into such common use.

Other forms may be employed embodying the features of my invention instead of the 55 one here explained, change being made in the form or construction, provided the elements stated by any of the following claims or the equivalent of such stated elements be employed, whether produced by my preferred method or by others embodying steps 60 equivalent to those stated in the following claims.

I therefore particularly point out and distinctly claim as my invention:—

65 1. A woven wire screen cloth comprising a relatively hard resilient screen body provided with softened marginal portions.

2. A woven wire screen cloth comprising a relatively hard resilient screen body provided with annealed marginal portions.

70 Signed by me this 19th day of March, 1919.

MORLEY PUNSHON REYNOLDS.
